UNITED STATES PATENT OFFICE.

LEONARD J. SMITH, OF DAYTON, OHIO.

COMBINATION END AND COUPLING FOR DISPLAY-CASES.

1,124,345.

Specification of Letters Patent.

Patented Jan. 12, 1915.

Application filed November 12, 1913. Serial No. 800,481.

To all whom it may concern:

Be it known that I, LEONARD J. SMITH, a citizen of the United States, residing at Dayton, in the county of Montgomery and State of Ohio, have invented certain new and useful Improvements in Combination Ends and Couplings for Display-Cases, of which the following is a specification.

My invention relates to display cases and particularly to a coupling member for connecting successive units or sections of display or show cases.

The object of the invention is to provide a coupling member simple in structure as well as in means and mode of operation which will not only be cheaper in construction, but will be efficient in use, easily assembled, readily accessible for cleaning or repairs and unlikely to get out of order.

It has heretofore been the custom to arrange show or display cases in retail stores end to end and in contact one with the other. Such show cases are usually constructed as complete units, that is, each show case is provided not only with rear, front and top walls, but with two end walls. The placing of such show cases end to end thus provides a double wall or partition usually of glass between show cases. Being placed closely adjacent, the intervening space between the parts of such double wall is usually too small to permit the cleaning of the adjacent faces of the glass. Dirt, dust and foreign matter collects in the intervening space and presents an unsightly appearance.

To obviate the foregoing difficulty and to provide means for coupling a series of show cases into a continuous structure having single partitions or division walls between succeeding units is one of the primary objects of the present invention.

Referring to the drawings, Figure 1 is a perspective view of the adjacent ends of two show case sections or units, separated one from the other, with the coupling member forming the subject matter hereof in place. Fig. 2 is a detail perspective view of the coupling member disconnected from the show case. Fig. 3 is a detail sectional view showing the relative location of the coupling member and the adjacent show case units. Fig. 4 is a detail sectional view showing the relative relation of the show case and the coupling member, when used

merely as an end wall at the end of the tier. Fig. 5 is a detail sectional view of the coupling member as constructed of sheet material.

Like parts are indicated by similar characters of reference throughout the several views.

In the drawings, 1 are show cases of ordinary construction, having side and top walls of glass. The adjacent end walls of such cases are removed and the coupling member forming the subject matter hereof is substituted therefor. This coupling member shown in detail in Fig. 2 comprises a frame 2 of a size equal to the end opening 3 70 of the show cases 1.

Secured within the frame 2 is a single glass plate 4. This glass plate 4 may be secured in any suitable manner.

In the drawings, strips of molding 5 are shown located at opposite sides of the glass and secured to the inner faces of the frame 2. A strip of packing material such as felt, is preferably through not necessarily interposed between the molding and the glass, as shown at 6. To provide for the ready replacement of the glass 4, in the event of breakage, one side of the frame 2 is slotted as shown at 7, through which slot the glass 4 may be slid into position between the moldings 5. The coupling member forms a single wall or partition between succeeding show cases. The end walls of the succeeding show cases being removed, the coupling member as shown in Fig. 2 is inserted 90 into one of the show cases the distance of one half of the thickness of the coupling as shown at the left in Fig. 1. The second show case is then abutted upon the end of the first show case unit in such position that the protruding half of the coupling member 2 will extend into the open end of the second unit.

The coupling member may be secured to the succeeding unit by means of screws, 100 nails, brads or other fastening devices extending through the molding and frame as shown in Fig. 3. It is obvious that rabbets might be formed in the open ends of the show cases to receive the coupling member. 105

At the end of the tier of show cases a coupling member is inserted within the open end of the case and adjusted flush therewith as shown in Fig. 4. If at any time additional show case units are to be added, this 110

terminal coupling member may be shifted outward and be made to engage the next succeeding unit herein before described.

In Fig. 5 there is shown a construction in which the frame of the coupling member is constructed of sheet metal, the opposite edges of the material being bent inward upon themselves to parallelism and the adjacent edges being extended perpendicular to the main portion of the frame to form flanges 9 spaced one from the other between which the glass 4 is inserted. This construction is employed in the same manner as the one before described.

From the above description it will be apparent that there is provided a device of the character described, possessing the particular features of advantage before enumerated as desirable, but which is obviously susceptible of modification in form, proportion, detail construction or arrangement of parts, without departing from the principle involved or sacrificing any of its advantages.

While in order to comply with the statute, the invention has been described in language more or less specific as to certain structural features, it is to be understood that the invention is not limited to any specific details but that the means and construction herein described comprise but one mode of putting the invention into effect, and the invention is therefore claimed broadly in any of its possible forms or modifications within the scope of the appended claims.

Having thus described my invention, I claim:

1. In a coupling member for display cases, the combination with two open ended cases located adjacent one to the other of a frame having a telescopic connection with the open ends of both cases and a partition wall carried by said frame, the construction

and arrangement being such that the frame may be adjusted to a position flush with the end of either case or may be extended simultaneously into both cases.

2. In a device as described, the combination with two display cases, of an end frame common to both cases telescoping within the adjacent ends of the cases and a partition wall carried by said telescoping frame, the construction and arrangement being such that the frame may be adjusted to a position flush with either case.

3. The combination with two adjoining cases each having an open end abutting the open ends of the other case, of a movable partition adjustable longitudinally in relation with the cases to positions wholly within either case or to a medial position in which the partition simultaneously engages in both cases.

4. The combination with a display case of a telescopic end section therefor, said telescopic end section being adjustable longitudinally to a position beyond the plane of the case, the projecting portion of the frame being adapted to extend within the open end of the next succeeding case.

5. The combination with a display case of a frame member having a slot in one side thereof and a partition plate slidably adjusted within the frame and removable therefrom through said slot, said frame being slideable laterally in the display case to bring the frame slot into and out of registry with the side wall of the case thereby opening and closing the slot.

In testimony whereof, I have hereunto set my hand this 3rd day of November, 1913.

LEONARD J. SMITH.
